CONSTRUCTION MATERIAL

Cedric Gibbons, Santa Monica, and Ernest H. Tate, Los Angeles, Calif., assignors to Metro-Goldwyn-Mayer Corporation, Culver City, Calif., a corporation of New York

Application July 23, 1929. Serial No. 382,810

2 Claims. (CL 154—44)

This invention relates to a new and novel construction material particularly adapted for use in the construction of stages and scenes used in the taking and recording of picture and sound records. The invention also relates to a method of making a light weight construction material for scene construction.

In the taking of motion picture records with accompanying sound records, the scenes are generally taken in large sound stages or buildings, which are thoroughly insulated against the passage of sounds from the exterior and provided with sound absorbing internal surfaces so as to prevent reverberation in the building per se. A plurality of scenes are generally constructed within the sound stage building. Heretofore scenes have been generally constructed of such materials as plaster board, paper board, wood, etc.

Even when such stages have been constructed of loosely felted fibrous boards, such as boards made from sugar cane bagasse, and the surfaces then painted to conform with the desired effect, a great deal of reverberation has been set up in the individual scenes. For this reason, in the taking of sound recording it has been substantially impossible to employ a scene having three walls, such as for example, the three walls of a room, as the reverberation set up in the space thus enclosed produces a sound record which is indistinct, mixed and muffled.

An object of this invention is to disclose and provide a construction material adapted to be used in scene construction which permits the erection of three or four sided scenes, capable of being used in the taking of sound records without producing undue reverberation.

Another object is to disclose and provide a construction material adapted for scene construction which is light in weight, porous, incapable of reflecting sound and capable of permitting the passage of sound therethrough.

Another object is to disclose and provide a construction material particularly adapted for scene construction which may be readily bent, curved, cut, nailed and rolled.

A still further object is to disclose and provide a construction material which may be colored readily, and which may be caused to assume different textures or surface characteristics.

Another object is to disclose and provide a method of making a construction material capable of permitting the passage of sound waves therethrough.

Another object is to disclose and provide a

method of making a porous construction material particularly adapted for use in scene construction.

Other objects, uses and advantages of the invention described hereinafter in detail will become apparent to those skilled in the art.

In describing the invention, reference will be had to the appended drawing, in which:

Fig. 1 is a perspective of a typical set or scene erected from a material made in accordance with this invention.

Fig. 2 is a section greatly enlarged, through a portion of the construction material made in accordance with this invention.

Fig. 3 is a diagrammatic representation of an apparatus which may be used in making the construction material embraced by this invention, it being understood that the arrangement of elements in such diagrammatic representation is merely illustrative of one method which may be employed and of one apparatus, and that numerous changes and modifications may be made without departing from the scope of this invention.

As shown in Fig. 1, it is very often desirable to erect a scene or set which contains at least three walls, such as the side walls 1 and 2, and an end wall 3. By employing the three side walls to a scene, a greater angle of view may be embraced and a greater fidelity of picture reproduction obtained. Furthermore, such construction permits the director and cameraman to most effectively direct the cameras or the lens of the camera, and most effectively group the actors.

The scene represented in Fig. 1 illustrates a medieval kitchen and includes a niche 4 in the far wall 3, which contains a curved or bee-hive oven 5. A door 6 is seen in an aperture or archway in the side wall 2.

The walls 1, 2 and 3 are, in accordance with this invention, preferably constructed of a foraminous material coated with a layer or layers of comminuted or fibrous material described in detail hereafter.

The foraminous material with its porous coating is preferably stretched upon a suitable framework 7 and maintained in the desired position by means of a false-work indicated generally at 8.

The construction material used in making the walls 1, 2, 3 and other portions of the scene, such as the niche 4 and the oven 5, comprises a foraminous base 9, preferably consisting of a wire mesh or netting. A screening having eight to twelve meshes per lineal inch has been found to be very satisfactory. Such foraminous base is then pref-

- erably coated with an adhesive material, such as for example, a glue solution, shellac, a lacquer or an asphaltic material, and a fibrous material, generally indicated at 10, then applied to the foraminous base before the adhesive has set or hardened. Sawdust, preferably screened so that material finer than about twenty-four mesh has been removed, is very suitable for use as the comminuted material for coating the foraminous base.
- 10 In order to create a coating of appreciable thickness, on the surface of the foraminous material 9, it may be necessary and desirable to spray the initial coating of comminuted or fibrous material 10 with an additional quantity of adhesive, and then apply a second layer of the comminuted or fibrous material thereto.
- The comminuted or fibrous material 10 may be applied to the foraminous base 9 by hand by being screened thereinto or by being blown thereon. The applications of adhesive and fibrous material are preferably made until a layer of fibrous material is formed on the foraminous material of a thickness capable of substantially preventing the passage of light therethrough.
- 25 Only a nominal amount of adhesive is to be applied to the subsequent coatings of fibrous material, so as to maintain the layer of fibrous material formed on the netting porous.
- A layer of fibrous or comminuted porous material applied in this manner to a netting may be smoothed or troweled so as to produce a smooth finish while the adhesive employed in attaching said porous or comminuted material to the netting is still plastic or semi-fluid. If, however, it is desired to produce a construction material having a rough or irregular surface (such as is obtained, for example, by a rough stucco finish) then the porous or fibrous material need not be troweled. It will be found that aggregates or lumps, such as for example the lump indicated at 11, will form over the surface of the netting and thus produce a rough surface.
- After a layer of such porous comminuted or fibrous material has been formed on the base of wire mesh or other foraminous material, it may be desirable to impart a suitable coloring thereto. In coloring construction materials of this character, it is undesirable to employ viscous paints which would tend to clog the porosities of the material.
- 55 Preferably, a construction material made as described hereinabove is sprayed with a dye capable of imparting a suitable color to the material without forming films or otherwise clogging the porosities of such material. Any suitable dye may be employed, the character of said dye varying somewhat with the character of the comminuted or fibrous material employed in making the construction material. If desired, the comminuted or fibrous material may be dyed before being applied to the netting, but the first named method is preferred.
- A construction material made in accordance with this invention is light in weight, flexible, 65 may be cut to desired shape, bent or curved, and may be readily attached to a false-work or other suitable support. Furthermore, the construction material is extremely porous, the porosities extending completely through the layer of material, and for this reason sound waves readily penetrate the material. As a result, a set or scene constructed therefrom may be used for the simultaneous recording of pictures and sound effects, even though a complete room with four walls and a ceiling is constructed therefrom, as the sounds will not reverberate from the walls or ceiling, but instead pass through said walls and be absorbed in said construction to a certain extent. The passage of light through such walls is substantially prevented, although a certain quantity of light may pass therethrough when only a very thin layer of a comminuted or fibrous material is applied to the netting.
- 80 It is to be understood that a material of the hereinabove described characteristics may be made in any suitable type of apparatus or by hand. In Fig. 3, however, there is shown diagrammatically an arrangement of elements of a machine which may be employed.
- 85 Referring to Fig. 3, a foraminous material such as a wire mesh from a roll 12 may be fed into a suitable tank or receptacle 13 supplied with an adhesive fluid 14. The wire mesh from roll 12 may pass under a weighted roller 15 so as to cause said mesh to be partly or completely submerged in the adhesive 14. The mesh may then pass over a roller 16, and then pass under a screen or distributing hopper 17 containing the fibrous, porous or comminuted material with which it is desired to coat the mesh.
- 90 The member 17 may comprise a plurality of sprays adapted to blow the fibrous material (such as sawdust) upon the mesh. A receptacle 18 may be positioned beneath the hopper or applying member 17, so as to attach any material which may pass through the mesh or netting. Excess comminuted or fibrous material may be removed from the netting by means of a flexible scraper or trowel 19. In order to apply further coatings of fibrous or comminuted material, the mesh with 95 one coating thereon may then pass over a roller 20, and then under a spray means 21 by means of which a light application of adhesive is made to the netting and fibrous material adhering thereto.
- 100 Additional quantities of fibrous material may then be applied in any suitable manner as by means of air blowing at 22, the excess being removed again (if necessary or desired) by means of a flexible scraper 23. The finished construction material may then be wound upon a reel 24.
- 105 The hereinabove described apparatus permits the continuous manufacture of a construction material described hereinabove, and such finished construction material may then be applied 110 to suitable false-work in the construction of stages or scenes and dyed after said material has been erected.
- 115 The hereinabove described apparatus permits the continuous manufacture of a construction material described hereinabove, and such finished construction material may then be applied 120 to suitable false-work in the construction of stages or scenes and dyed after said material has been erected.
- 125 It is to be understood that numerous changes and modifications can be made in the method of 130 making the material without departing from this invention. For example, the netting or foraminous material may be applied to the false-work and a complete set or scene constructed therefrom, and such scene or set then alternately 135 sprayed with adhesive and fibrous or comminuted porous material so as to form the coating directly upon the set or scene. This method may be particularly useful when the set or scene contains a large number of curves, niches, doorways and 140 the like, as all joints and laps may be readily covered and concealed. The finished structures made from a construction material embraced by this invention have every characteristic of solidity and strength, although they are extremely 145 porous and light.
- We claim:
1. A construction material for scene construction having porosities extending completely therethrough, said construction material com-

prising a foraminous material having a layer of comminuted porous material carried thereby, an adhesive being carried by said foraminous material in quantity sufficient to cause said porous material to adhere thereto but insufficient to fill the openings of said foraminous material.

2. A construction material for scene construction having porosities extending completely therethrough, said construction material comprising a foraminous material having a layer of

sawdust carried thereby, an adhesive being carried by said foraminous material in quantity sufficient to cause said sawdust to adhere thereto but insufficient to fill the openings of said foraminous material nor coat the surfaces of 80 particles of said sawdust to seal the inherent porosities thereof.
